UNITED STATES PATENT OFFICE.

EARL H. RICHARDSON, OF ONTARIO, CALIFORNIA, ASSIGNOR TO PACIFIC ELECTRIC HEATING COMPANY, OF LOS ANGELES, CALIFORNIA, A CORPORATION OF CALIFORNIA.

SUSPENSION-BRACKET.

No. 868,888.

Specification of Letters Patent.

Patented Oct. 22, 1907.

Application filed September 27, 1906. Serial No. 336,516.

To all whom it may concern:

Be it known that I, EARL H. RICHARDSON, a citizen of the United States, residing at Ontario, in the county of San Bernardino and State of California, have invented a new and useful Suspension-Bracket, of which the following is a specification.

This invention relates to a suspension bracket adapted for use in laundries; and one of the main objects of the invention is to provide a bracket for suspending a lighting fixture and for suspending in a convenient position above the ironing board an insulated wire which conducts electricity to the laundry iron.

A further object is to provide a stand on said bracket which is adapted to support the laundry iron, when not in use, in a position within convenient reach, and yet entirely out of the way of the operative, leaving the greater portion of the upper surface of the ironing board unobstructed, thus not only preventing possible scorching of the ironing board or any piece thereon, but also permitting the ready removal of any piece which has been ironed from the board, a further object being to make the stand adjustable on the bracket so that its position can easily be regulated to suit the operative, and to also make the bracket adjustable to enable the operative to adjust the light and cord in the most convenient position.

A further object is to support the cord with a resilient extensible connection which allows the cord to follow the iron in its movement and takes up slack in the cord, and which retracts the cord and holds the plug above the board when the plug is disconnected from the iron; and to provide simple but effective means whereby the cord is adjustably connected with said extensible connection to enable the length of that portion of the cord which extends below said resilient connection to be varied according to the necessities of the work and convenience of the operative.

The accompanying drawings illustrate the invention, and referring thereto:—Figure 1 is a perspective view illustrating an ironing board equipped with the invention, the laundry iron being shown on its rest, disconnected from the plug and cord, the dotted lines illustrating the iron when connected as in use. Fig. 2 is a detail view, in side elevation, of the lower part of the bracket, showing the rest and the laundry iron standing thereon. Fig. 3 is a detail view illustrating the manner of attaching the cord to the spring.

1 designates the ironing board which projects from the wall 2. A base 3 is fastened to the upper face of the ironing board 1, preferably near the wall 2, in any preferred manner, for example, by screws 4 which pass through lugs 5 and 6, the lug 6 being longer than the others and extending in a direction away from the wall giving a stable support to the base. The base is provided with a socket 7 which is strengthened by ribs 8

and 9, which socket receives the lower end of a bracket 10, which is retained therein by a set screw 11, affording means for revolvably adjusting the bracket 10 in the socket. A rest 12 is attached to the bracket 10 and comprises a shelf 13 which projects from a collar 14, through which the bracket 10 projects, the collar being fastened to the leg of the bracket by a set screw 15, which enables the rest 12 to be swung around on the bracket 10 and adjusted in the desired position. The shelf 13 is preferably provided with a slightly raised flange 16 which conforms to the contour of the sole of the laundry iron 17, and prevents the laundry iron from accidentally slipping out of place and falling from the shelf.

The upper part of the bracket 10 is formed with a gooseneck 18, from the end of which is suspended a fixture 19, from which hangs a fixture tube 20 and a heating cord 21, wires being conducted thereto through the hollow bracket 10. A lamp 22 is connected to the lower end of the tube 20 and supports the light in a position above the ironing board 1. An auxiliary or extension bracket 23 is attached to the goose-neck 18 and supports a coil spring 24 to which the heating cord 21 is adjustably connected, as shown in Fig. 3, by means of a leather loop 25 comprising a thong with a slit near one end through which the other end of the thong passes, thereby forming a slip noose, which is hung from a hook 26 formed at the lower end of the coil spring 24. The length of that portion of the heating cord 21 which lies below the spring 24 may be regulated by loosening the noose and slipping the heating cord there through to the place desired and then drawing the noose 25 tight. As the weight of the cord 21 tends to tighten the noose and cause the cord to bind therein the cord is securely held from accidentally slipping through the noose. The lower end of the heating cord 21 is connected to a plug 27, which is adapted to be removably inserted in a plug receptacle 28 on the laundry iron.

The piece to be ironed, as indicated at 29 by dotted lines in Fig. 1, is arranged on the ironing board 1, the plug 27 is connected with the iron and as the laundry iron is manipulated the spring 24 will alternately yield and contract to permit of the necessary movement of the cord 21, the spring 24 being very flexible, and while having the necessary strength to support the weight of the cord 21, is not strong enough to cause the plug 27 to be pulled out of the receptacle 28 when the laundry iron is moved to a far position. When the piece is ironed and ready to be removed, the plug 27 is pulled out of the receptacle 28 and the laundry iron is placed on the rest 12 where it is out of the way, and the spring 24 contracts and holds the plug 27 up out of the way, permitting the removal of the piece which has been ironed and the placing of another piece to be ironed on the board.

By loosening the screw 11 the bracket 10 may be 110

swung around to place the lamp 22 in the most convenient position, and if in this adjustment the bracket 10 is moved considerably away from the ironing board then it may be advisable to readjust the heating cord 5 21 at the loop 25, to enable the cord to reach the laundry iron without greatly stretching the spring 24, as the spring 24 should preferably be relaxed or substantially so when the laundry iron on the piece being ironed is nearest in an air line to the spring, otherwise the tension 10 of the spring might be increased unduly during certain positions of the laundry iron.

What I claim is:—

1. A base adapted to be attached to the ironing board, a bracket adjustably mounted on said base, an auxiliary bracket on the first bracket, a coil spring hung from the auxiliary bracket, a fixture on one of said brackets, and a heating cord extending from the fixture to the lower end of the spring and hanging from the spring with its lower end adapted to be connected to the laundry iron. 15
2. A base adapted to be attached to the ironing board, a bracket adjustably mounted on said base, a laundry iron rest adjustable on said first bracket, an auxiliary bracket on the first bracket, a coil spring hung from the auxiliary bracket, a fixture on one of said brackets, and a heating 20 cord extending from the fixture to the lower end of the spring and hanging from the spring with its lower end adapted to be connected to the laundry iron. 25

3. A base adapted to be attached to the ironing board or other support, a socket on the base, a bracket with its leg revolvably mounted in said socket, means for clamping said leg in the socket, a rest comprising a sleeve with a projecting shelf having a retaining flange for supporting the laundry iron, the sleeve being revolvably mounted on said leg, means for clamping the sleeve on the leg, an auxiliary bracket on the first bracket, a coil spring connected 30 to the auxiliary bracket, a heating cord extending through the bracket, a thong forming a noose which receives the heating cord and connected to the spring, the heating cord having a detachable connection with the laundry iron. 35

4. A base adapted to be attached to the ironing board or other support, a socket on the base, a bracket with its leg revolvably mounted in said socket, means for clamping said leg in the socket, a rest comprising a sleeve with a projecting shelf having a retaining flange for supporting the laundry iron, the sleeve being revolvably mounted on said 40 leg, means for clamping the sleeve on the leg, an auxiliary bracket on the first bracket, a coil spring connected to the auxiliary bracket, a heating cord extending through the bracket, means whereby the heating cord may be attached at any desired point to the end of said spring, the heating 45 cord having a detachable connection with the laundry iron.

In testimony whereof, I have hereunto set my hand at Ontario California this 18th day of September 1906.

EARL H. RICHARDSON.

In presence of—

I. HAMMOND.
C. V. SMITH.
